(57) **CLAIM**

The ornamental design for a coffee machine, as shown and described.

DESCRIPTION

FIG. 1 is a front perspective view of an ornamental design for a coffee machine according to the present invention;
FIG. 2 is a front elevational view of the coffee machine of FIG. 1;

FIG. 3 is a rear elevational view of the coffee machine of FIG. 1;

FIG. 4 is a left side elevational view of the coffee machine of FIG. 1;

FIG. 5 is a right side elevational view of the coffee machine of FIG. 1;

FIG. 6 is a top plan view of the coffee machine of FIG. 1; and,

FIG. 7 is a bottom plan view of the coffee machine of FIG. 1.

The broken lines shown in FIGS. 1-7 are for the purpose of illustrating environmental structure and form no part of the claimed design.

1 Claim, 7 Drawing Sheets
